CLAIM

The ornamental design for a visor, as shown and described.

DESCRIPTION

FIG. 1 is a top plan view of a visor showing my new design the dashed lines represent conventional stitching;

FIG. 2 is a right side elevational view thereof;

FIG. 3 is a left side elevational view thereof;

FIG. 4 is a bottom plan view thereof;

FIG. 5 is a front elevational view thereof;

FIG. 6 is a rear elevational view thereof; and,

FIG. 7 is a perspective view of a visor positioned on the head of a person, the broken lines showing the head are for illustrative purposes only and form no part of the claimed design.
